UNITED STATES PATENT OFFICE.

STEPHEN C. HOUGHTON, OF SAN FRANCISCO, CALIFORNIA, ASSIGNOR TO
THE HOUGHTON REGISTER COMPANY, OF CALIFORNIA.

FARE-REGISTER.

SPECIFICATION forming part of Letters Patent No. 628,223, dated July 4, 1899.

Application filed June 23, 1898. Serial No. 684,243. (No model.)

To all whom it may concern:

Be it known that I, STEPHEN C. HOUGHTON, a citizen of the United States, residing at San Francisco, in the county of San Francisco and State of California, have invented certain new and useful Improvements in Fare-Registers, of which the following is a specification.

My invention relates to registers, and more particularly to the registers used in railway-cars for indicating the receipt of fares. It also belongs to the general style or type of registers described and shown in Letters Patent granted to me May 2, 1893, No. 496,688, and August 27, 1895, No. 545,291, and contains improvements upon the mechanisms described in those patents.

Like the register described in the patent last mentioned, the present construction is a duplicate register, in which cash fares and transfers are separately registered, and each separate register consists of two parts or mechanisms, one being a trip-register, acting in sequence for a trip, and the other a total-register, acting in sequence up to the limit of its capacity for indication. The trip-register and total-register are connected during the trip, so that one actuating means operates both; but provision is made at the end of the trip for disconnecting them and for resetting the trip-register for another trip without affecting the total-register. The resetting means act upon both the sets of trip-registers referred to. Some of my present improvements relate specially to these resetting devices as applied to two independent trip-registers. Some of them relate to features of construction, which may be a part of a single register, as well as of the duplicate registers referred to. Others relate to the automatic disconnection of the trip and total registers by the resetting mechanism; others to the alarm or bell mechanism; others to means for controlling the application of an electric current when the registers are electrically operated, and others to a recording mechanism in conjunction with the registering mechanisms, by means of which record impressions of totals can be secured at any desired time and which can be arranged to give record impressions of both cash-fare and transfer totals simultaneously and by a single operation.

I have embodied my present improvements in a mechanical construction, which is hereinafter described in connection with the accompanying drawings.

55

In the drawings, Figure 1 is a perspective view of the interior of a railway car, showing a fare-register in position, means for electrically operating it, and the circuit-controller. Fig. 2 is a detail cross-section showing the conductors or contacts which extend through the car and illustrating the operation of the circuit-controller in connection with said conductors. Fig. 3 is a plan of the register with the top of its casing partly broken away to show the interior mechanism. Fig. 4 is a front elevation of the same with a portion of the front casing broken away. Fig. 5 is a detail elevation showing the means for giving the primary or initial movement to the register mechanisms and showing also the alarm mechanism at rest. Fig. 6 is a similar elevation illustrating a peculiar change in leverage for operating the bell-striker. Fig. 7 is a similar view showing the same parts in the position they assume after the register has been operated and just before the bell-striker is released. Fig. 8 is a similar elevation showing particularly the means for operating the trip and total cash-registers. Figs. 9 and 10 are front elevations of the several indicating-dials of the register, showing two positions of the resetting mechanism and locking devices for the latter. Figs. 11 and 12 are end elevations in different positions of the devices for disconnecting the trip-register from the total-register for the purpose of resetting the former. Figs. 13 and 14 are plan views of the same. Fig. 15 is a plan of the lock for the direction-indicator. Fig. 16 is an elevation to illustrate the operation of the recording mechanism. Fig. 17 is a bottom plan of the same with the support for the record-blank removed. Fig. 18 is a bottom plan of the same with the support in position. Fig. 19 is an end elevation of the same. Fig. 20 is a cross-section of co-operating units and tens recording-wheels. Fig. 21 is an elevation of one of such wheels and of the means for controlling its actuating mechanism.

95

100

A register A shown in the drawings and herein described is electrically operated—

that is, it is controlled by an electromagnet B, whose armature B' is a lever having mechanically operative connections with the registering apparatus. This magnet is included 5 in an electric circuit upon the car, having a controller which is operated by the fare-collector. For this electrical action mechanical action can be substituted without any material change in the construction of the register, since it is only necessary to operate the lever B' by a mechanical pull instead of by 10 an electrical impulse transmitted to it as an armature. The electrical feature of the device when employed ends with the transmission of motion to the primary operating means, which is this armature-lever B'.

The wires *xy* from the magnet are connected to conductors X Y, which are also contacts and which extend along the car in a groove 15 shown as located near the lower edge of the ordinary raised ventilating structure.

The circuit-controller Z is a strip hinged at the bottom of the groove and extending along the car, so that it may be pressed inwardly 20 by the fare-collector at any point in its length. This strip carries the conductor X, while the conductor Y is fixed opposite and at the bottom of the groove. A spring or series of springs *z* return the strip Z to normal position after each pressure. At each collection 25 the strip is pressed, closing the circuit through the contacts X and Y, energizing the magnet and attracting the armature-lever B'. A battery is conventionally shown at X' in the 30 wire *y*.

The register-casing A may be a box of any suitable design and construction and is provided with a front plate having a number of visual openings to exhibit numerals and combinations of numerals carried by indicating-dials within the box. The register comprises 40 a set of trip-registers and a set of total-registers for cash fares with operating mechanism and located at one end of the box and a set 45 of trip-registers and a set of total-registers for transfers with operating mechanism located at the other end of the box. These cash and transfer registers are independently operated either electrically or mechanically, 50 and as I am assuming an electrical operation in the present case it will be understood that the electrical connections heretofore described are duplicated and placed, preferably, in the same relative position upon the opposite side of the car in order to operate the transfer-registers. It will be also understood 55 that in describing the cash-fare-registry mechanism at one end of the box I am also describing similar transfer-registry mechanism 60 at the other end.

Referring first to Figs. 3 and 4 in connection with Figs. 5 to 8, inclusive, the operation of the register commences with the intermittent rotation of an arbor 1, journaled in bearings in a frame A' within the casing and having a loose ratchet 2, which is engaged and moved step by step by the pawl 3, pivoted

upon the lever B', which in this instance and as before stated is the armature of the magnet B. The ratchet is prevented from backward movement by a holding pawl or dog 4, pivoted to the fixed bracket 5, through which the arbor passes and which is pressed by a spring 6 into engagement with the toothed wheel 7, the latter being secured to the ratchet 75 2. The loose ratchet 2 transmits motion to the arbor, being detachably connected to a disk D by a clutch and the disk being tight on the arbor. The clutch will be more fully described in connection with the resetting 80 mechanism; but as the parts are now being described as in their normal operative relations it is unnecessary to do more than refer to it in this place. The arbor 1 carries the units-dial U, which bears on its face the numerals from "0" to "9," inclusive. Such a dial on the transfer side of the register is shown in Fig. 4 at U' in the same relative position as the dial U on the cash side. This dial comprises part of the trip-register upon one side 85 of the box, the other member being a tens-dial T, mounted on an arbor 8 and overlapping the units-dial, Fig. 3. Such a dial T is shown in Fig. 4 on the transfer side of the register, bearing numerals from "0" to "9" and 90 coöperating with the units-dial in successively displaying the trip-collections at the openings in the front plate. The arbor of the tens-dial is operated one step at each revolution of the units-dial and just before the completion of such revolution, the actuating means 95 being the disk D, which is provided with a tooth 9. This tooth engages successively with teeth 10 on a disk E, loosely mounted upon the arbor 8, Figs. 4 and 8, causing the 100 units and tens dials to register successively up to "99" in the manner illustrated on the transfer side of Fig. 4. While the units-dial is making its step-by-step rotation and the tens-dial is at rest, the arbor 8 is locked by 105 an automatically-acting pawl 11, Fig. 8. This pawl is pivoted upon a pin 41 in a fixed bracket of the frame A' and is provided with a weight-lever 13, which tends to hold its rounded end in engagement between two of 110 the teeth 10 and in contact with the concentric periphery of the disk D, thus locking the disk E, its arbor, and the tens-dial against motion in either direction. In the periphery of the disk D and behind the tooth 9 is a 115 curved recess 14, into which at the instant of actuating the disk E the rounded end of the pawl 11 is forced, leaving the disk E free to be moved, the pawl remaining in the recess until upon the disengagement of the co-operating teeth it emerges and rides again 120 upon the concentric periphery of the disk D and in locking position. While the trip-dials are making their indications, a set of total-dials are also registering, their motion 125 being derived from the arbor 1 of the trip units-dial. Loose on the arbor 1, because in fixed relation to the ratchet 2, is a pinion 15, which meshes with a gear 16 on a shaft 17.

The arbor 18 of the units-dial in the total-register has a pinion 19, which derives motion from the gear 16, Fig. 8. Four total-dials are shown in the drawings (dotted lines 5 in Fig. 4) at *u*, *t*, *h*, and *th*, carried, respectively, upon the arbors 18, 20, 21, and 22. Upon the first three of these arbors are actuating-disks 23, each having a tooth and a peripheral recess like those before described. 10 Upon the last three of the arbors are actuated toothed wheels 24, like the one *E*, before described, and between the respective disks 23 and wheels 24 are locking-pawl 25, like the pawl 11, before described. It will 15 now be clear that at the commencement of the work of the register and with all the dials at zero the trip-register and total-register will as fares are collected be operated simultaneously to give consecutive indications, the operation of the first being limited to a trip, while that of the latter is unlimited, excepting by its own capacity for registration. Whenever the lever *B'* is pulled electrically or mechanically to register a fare, an alarm 20 is sounded to give notice of the fact. This alarm is preferably a bell *F*, mounted upon the back plate of the casing, Fig. 3. The operation of this alarm, which is caused by peculiar and novel mechanical connections, is 25 best illustrated in Figs. 5, 6, and 7. The object in view is to have the first pull of the lever *B'* (especially when it is an armature) act through a very long and favorable leverage upon a bell-striker connected to it, so 30 that at first, when the magnetic attraction is feeble, the lever is practically relieved of the weight and resistance of the striker. After- 35 ward as the armature-lever passes more completely into the magnetic field and is attracted 40 with greater power the fulcrum or point of resistance of the bell-striker is changed in such a way that the striker is suddenly thrown out away from the bell by power applied through a short leverage, attaining its limit 45 of motion in that direction at the time when the armature has been fully attracted. The bell-striker *F'* is pivoted at 26, near the upper end of lever *B'*, so that its long arm, carrying the hammer, projects downwardly to- 50 ward the bell, while a short arm projects upwardly beyond the pivotal point 26. When at rest, the lower end of the striker bears against a spring-buffer 27, located adjacent to the bell, Fig. 5, and a coil-spring 28 tends 55 to keep it in that position. When the magnet is energized and the armature commences to move, motion is transmitted to the upper end of the bell-striker as to a lever of the second class, in which the fulcrum is at the op- 60 posite end—in this case the buffer 27. The resistance to a leverage so favorable as this is very slight, and the upper end of the striker continues to shift until it is arrested by a stop 29, Fig. 6. The armature is now being 65 strongly attracted, and so although the leverage is now less favorable on account of the short distance between the pivot 26 and stop

29 the lower end of the bell-striker is thrown sharply over to the position of Fig. 7. When the armature is released, the spring 28 pulls 70 the striker toward the bell. Its momentum overcomes the resistance of the spring-buffer 27, and the bell is struck; but the spring 27 immediately recovers and holds the striker out in normal position, Fig. 5. This insures 75 a clear tone at each stroke without repetitions or blurring. The return stroke of the armature *B'* is limited by a stop 31.

In a preceding part of the specification I referred to the fact that the ratchet 2 on arbor 1 was detachably connected to the disk *D* by a clutch. The purpose of this disconnection is to allow the dials of the trip-register to be reset to zero without affecting the dials of the total-register. The parts which are 80 disconnected from the actuating-disk *D* are the ratchet 2, holding-ratchet 7, and pinion 15, which are all secured together. The clutch is composed of pins 32, projecting from pinion 15 and which normally enter sockets 33 85 in a shoulder 34, forming part of the disk *D*. This construction is best shown in Figs. 11 to 14, to which special reference is now made. By sliding the movable parts just referred to along the arbor 1 the trip and total registers 90 are disconnected, Fig. 14, from their normal relations, Fig. 13, but without disconnecting the total-register from its actuating-gearing. The disengagement of the clutch is accomplished by devices operated by the act of re- 95 setting the trip-dials to zero at the end of any trip. The resetter is a pull-down bar *G*, having a convenient operating-handle projecting from the bottom of the casing. The bar *G* slides in guides 35 on the frame *A'*. At the 100 upper end of the bar is the cross-arm *G'*, extending both into the cash end and transfer end of the casing and carrying at each end the pointed pins 36 37. These pins are located in line with the respective arbors 1 and 105 8, upon which are fixed the heart-shaped cams 38 and 39. The positions of these cams upon their arbors bear definite relations to the positions of the zeros on the tens and units dials of the trip-register. In resetting 110 these dials the pins 36 and 37 revolve the heart-shaped cams from whatever position they may have reached—*e. g.*, that of Fig. 9—to the positions of Fig. 10, when the cams come to rest, with the pins in the depressions incident to their heart shape and both disks at zero. Of course before the pins 36 and 37 have 115 engaged these cams the disconnection of the clutch-pins 32 and the shifting of the actuating devices of the trip-register have been accomplished, and this is done by means operated by the movement of the pull-down bar and its cross-arm *G'*. Upon the cross-arm is a beveled projection 40, which acts as a cam against the end of the sliding pin 41, mounted in the frame *A'*. This is shown generally in Fig. 4 and in detail in Figs. 11 to 14. The pin 41 has been referred to before as the pivotal mounting for the locking-pawl 11 be- 120 125 130

tween the disks D and E. A clutch-shipper I is held upon the pin 41 between the hub of pawl 11 and a pressure-spring 42, the latter bearing against a stop 43 on the frame. This 5 spring holds the sliding pin and locking-pawl in normal position, Fig. 12, in the path of the cam 40. An arm I' of the shipper extends to and fits between the ratchet 2 and the gear 15. Another arm I² of the shipper extends 10 to and is mounted upon the arbor 8 of the tens trip-dial, where it is connected to the hub of the toothed disk E. The movement of the pin 41 therefore not only disengages the trip-register from the total-register, but 15 also disconnects the units and tens dials of the trip-register, because the shipper-arm I² moves the disk E out of line with the tooth of disk D, Fig. 14, and the pin 41 directly carries the locking-pawl 11 out of line with 20 the disk D, Fig. 12. When the pin 41 is freed by the return of the pull-down bar, the spring 42 returns the pin, shipper-arms, and parts controlled by them to normal position, Figs. 11 and 13. The resetter and its cross-arm 25 may be returned after each pull down by springs, such as those shown at 44 in Figs. 4 and 10.

In order that the pull-down bar shall make its full strokes both upwardly and downwardly, and thus insure the resetting of the trip-register, means are provided for locking it against a return after either stroke has commenced and before it has been completed. These means are shown in Fig. 4 in connection with Figs. 9 and 10. Secured to one edge 30 of the pull-down bar is a rack 45, consisting of a series of pointed teeth of regular size, with a single tooth 46 of larger size placed among them. Adjacent to this rack and pivoted in the frame A' is a dog 47, having at its ends teeth 48, 49, adapted to engage alternately with the rack. The dog extends beyond its pivot and terminates in a wedge-shaped or double-beveled extremity 50. A spring 51, 35 having an angular free end, bears upon one side or the other of the wedge-shaped end. In Fig. 9, which shows the parts in position previous to the resetting down-pull, the spring bears on the upper side of the wedge and 40 throws the tooth 49 into engagement with the rack. This tooth will allow of the downward movement, but will instantly lock the pull-down bar should it be released before it has reached the end of the downward stroke. Just 45 before this limit of movement is attained the large tooth 46 throws the lower end of the dog outwardly and its wedge-shaped extremity upwardly, Fig. 10, so that the tooth 48 engages with the rack and the spring 51 bears 50 upon the lower face of the wedge, compelling a full upward stroke of the pull-down bar. At about the end of such stroke the tooth 46 returns the dog and its spring to the position of Fig. 9. The pull-down bar also operates a 55 dial K, which indicates the direction of the trip, usually by the words "out" and "in." This dial, like the others described, is visible

through an aperture in the front of the casing, and its construction and operating and locking means are shown in Figs. 4, 9, and 10 in connection with the detail view Fig. 15. The dial K is mounted upon a shaft 52, having a bearing in or upon the frame A' and which extends through a longitudinal slot in the resetting-bar. Fixed also upon the shaft 70 52 is a plate 53, preferably of square shape and provided with forwardly-projecting pins 54. These pins are engaged successively and at each resetting of the register by an acute-angular projection 55, forming part of a pawl 56, 80 pivoted upon the pull-down bar and held in operative position by a spring 57. The pull-down of the resetter imparts a quarter-turn to this plate and to the shaft 52 and dial K. The return of the resetter produces no effect 85 upon the direction-indicator, since the incline of projection 55 rides over the pin 54. The indicator is therefore and in this instance provided with two sets of direction-terms and uses them in succession "in" and "out" alternately during its intermittent rotation, which when a four-sided controller is used occupies 90 four trips. The plate 53 is prevented from accidental or irregular movement by a spring 58, which bears against one of its straight 95 sides. An auxiliary and automatic lock for the plate 53 is also provided by the angularly-disposed lugs 59 upon the face of the pull-down bar and which inclose two sides of the plate 53 when the parts are in normal position, as in Fig. 4. These lugs release the plate 100 53 before the pawl 56 engages a pin 54.

In Figs. 16 to 21, inclusive, are shown a recording mechanism by means of which the totals of both trip cash and transfer registers 105 can be printed or otherwise impressed at any time, and as it is most convenient in practice to secure this record at the end of each trip I have utilized the trip-register-resetting device to operate the recording mechanism. In the 110 figures referred to such recording mechanisms are shown in connection with both cash and transfer registers, deriving their motions from being geared to said registers and moving uniformly in time with them. The resetting 115 action automatically impresses the periodical total-record, and then and automatically disconnects the gearing of the recorder from the gearing of the register and resets the recorder at zero. 120

The recorder shown in the drawings comprises a units-wheel and a tens-wheel for recording periodical cash-fare totals and a units-wheel and a tens-wheel for recording periodical transfer totals. In order to make the 125 construction as compact as possible and to use the resetting-bar with as few connections as practicable, I have arranged both sets of recorders upon a single shaft, where they are driven independently of one another by their 130 respective cash and transfer registers, but are operated as recorders and are reset to zero simultaneously.

The recording-wheels are carried by a pin

60, which is supported in the frame A'. The units-wheel 61 and tens-wheel 62 of the cash-fare register are loose on the pin, and each is formed with or secured to a heart-shaped cam 63. A gear 64 on the pin 60 is normally engaged with the cam of the units-wheel, preferably by clutch-pins like the pin 32 heretofore described, but is capable of being shifted on the pin in order to leave the units-wheel 60 free for resetting. This gear 64 and another 65 form a train which derives motion from the pinion 16, by which, as before described, the total-cash-fare register is driven. The units-wheel 66 and tens-wheel 67 of the transfer-recorder are also provided with heart-shaped cams and with a detachable gear 68, and this gear is normally in engagement with the transfer-register through a train 69, 70, 71 72, Figs. 16 and 17. Each units-record wheel is thus moved independently and in time with its respective register mechanism. It carries on its periphery impression means, which in this case are assumed to be sharp-edged type capable of making a clear impression upon a soft card or strip of paper, and these type are arranged in correspondence with the numerals on the units-disk of the trip-register. The units-disk before completing each of its revolutions engages and moves the tens-wheel one step in order to produce the combination for recording up to "99." As shown in Fig. 20, the units and tens wheels are placed side by side on the pin 60, and the tens-wheel is recessed, so as to provide a peripheral flange 73. In and next to this flange are a series of openings 74, spaced at registration intervals. A cam 75 is pivoted to the adjacent face of the units-wheel whose effective end 76 is normally held out of engagement with these recesses by a spring 77. Its other end 78, however, will at the proper time be obstructed by an arm 79, Fig. 21, which for the purpose of this particular operation may be considered as a fixed part, although it is in reality attached to movable mechanism. This arm has a curved inner edge 80, which is concentric with the disk, and hence holds the cam in engagement with the tens-wheel while the end 78 is traveling along the curve—i. e., during the period of movement of the tens-wheel. When the end 78 passes off the curve, the spring 77 disengages the pawl and releases the tens-wheel. A spring 95 normally steadies the latter.

55 As in this case I have described the totals as recorded at the end of a trip, I prefer to cause the trip-register-resetting mechanism to cause the record-impression to be made. The pull-down bar G has a pin 81, which at the commencement of the resetting movement strikes the beveled end of an angle-lever 82, pivoted at its angle. The farther or horizontal end of this lever rests beneath a lip 83 of a support 84 for a record-blank, the latter being pivoted at 85 in the frame and having a flat surface beneath the recording-wheels. A card, paper, strip, or other suit-

able record-blank is passed through a slot in the register-casing previous to resetting, Fig. 19, and rests upon the support. The resetting-action causes the support to be lifted, forcing the paper against the type and causing an impression to be made of the total indicated by both sets of record-wheels simultaneously. Immediately after the completion of the record the gears of the recorder are shifted, followed at once by the resetting of both sets of record-wheels to zero, all having been accomplished at the time when the down-stroke of the resetting-bar terminates.

Pivoted upon a pin 86, fixed in a part 88 of the frame A', is a sleeve 87, Figs. 16 and 19, from which an arm 89 projects toward the pull-down bar and beneath a stud 90 on said bar. The distance between the stud and arm 85 is sufficiently greater than that between the pin 81 and lever 82 to cause the operation of the arm 89 after the support has been lifted and the impression made. The sleeve carries four lever-arms 91, which terminate near the heart-shaped cams on the several units and tens wheels. Two of these arms also carry shipping-levers 92, having inclines which act as cams against flanges 93, secured to the hubs of the gears 64 and 68. It will also be noted that the arms 79, which cause the operation of cams 75, are secured to the levers 90, whereby such arms 79 are removed from the path of the pawl 75 at the time of resetting. The gears are shifted against the pressure of springs 94, which return them to position and engagement as soon as the upstroke of the resetting-bar commences. Reference to Fig. 16 will show that the shipping-levers take effect to shift the gears before the arms 91 come into contact with the heart-cams, so that the gears have been released and the cams and record-disks left loose on their shaft and pin by the time the arms 91 commence to revolve the heart-cams to the position in which they can rest in the depression of such cams, which will be at the moment when the record-disks have arrived at the zero-point. The sleeve 87 and the parts carried by it can be returned to normal position by a spring—such, for instance, as that shown at 96, Fig. 19. Both cash and transfer total recorders have now been reset to their zero-points, while simultaneously both trip-registers have in the manner before described also been reset. The trip-register is perfectly checked by the paper-record.

I do not limit myself to the precise and particular construction herein described and illustrated, as I desire to avail myself of the benefits of such modifications and equivalents as are properly within the spirit of my invention.

Having thus described my invention, what I claim as new, and desire to secure by Letters Patent, is—

1. In a fare-register, a box or casing, two sets of trip-registers and two sets of recording devices, in combination with a separate

resetting device having connections to act upon both sets of trip-registers and both sets of recording devices, and a movable part accessible outside of the closed casing for operating said resetting device, whereby all the trip-registers and all the recorders are reset at one operation.

2. In a fare-register, registering-wheels, and separate recording-wheels geared together for normal synchronous movement, in combination with such gearing, and with a separate resetting device having connections for disengaging both sets of wheels from the gearing and for resetting both sets of wheels after the disengagement.

3. In a fare-register, two sets of registers independently operable, a shaft intermediate said registers, a gear-train from said shaft to each set of registers, and two sets of recording-wheels mounted upon said shaft and driven independently by the respective gear-trains.

4. In a fare-register, a trip-register comprising counting-wheels, and a recording device comprising impressing-wheels, said register and said recording device being normally geared together, but both being capable of disconnection from the gearing, in combination with a pull-down bar and with means operated by said bar for first disconnecting the gearing, and then resetting both the trip-register and the recording device.

5. In a fare-register, a trip-register and a total-register, normally geared together but capable of disengagement to permit the resetting of the trip-register, an independent set of counting and recording wheels normally geared to the trip and total registers but capable of disengagement to permit them to be reset, and means for resetting the trip-register and the recording-wheels.

6. In a fare-register and in combination, two trip-registers independently operable, two total-registers geared respectively thereto, two sets of recording-wheels geared respectively thereto, detachable members in the gearing to enable both trip-registers and both sets of recording-wheels to be disconnected, and a resetting device having means for effecting such disconnection and for resetting the trip-registers and the recording-wheels.

7. In a fare-register the combination with separate cash and transfer registers, of sets of recording-wheels, mounted upon a common shaft, and each set comprising a plurality of counting and impressing wheels counting in sequence by periodical connection with and disconnection from one another, means for controlling said connection and disconnection, detachable gearing for operating each set of wheels as counters, and a movable bar having means for simultaneously disconnecting both sets of wheels from their gearing, and having also means for simultaneously resetting both sets of wheels.

8. In a fare-register and in combination, two sets of trip-registers, two sets of total-reg-

isters and two sets of counting and recording wheels, a set of each being geared together for normal synchronous movement; detachable members in the gearing to permit the trip-registers and the recording-wheels to be disconnected from the gearing, a support for a record-blank adjacent to the recording-wheels; and a pull-down bar carrying means for accomplishing through suitable connections and at a single stroke the following results; the impressing of a record by the recording-wheels, the disconnection of both sets of trip-registers and both sets of recording-wheels from the gearing; and the simultaneous resetting of all the trip-registers and all the recording-wheels.

9. In combination with a car, and electrical means for operating a register or like mechanism, electrical contacts mounted in the car structure, and a movable strip extending longitudinally on the car, and adapted to make such contacts by pressure at any point in its longitudinal extent.

10. In combination with a fare-register for cars, and with a magnet for operating the same, conductors or contacts extending longitudinally upon the car, and a movable strip extending longitudinally upon the car, in proximity to said contacts.

11. In combination with a fare-register for cars, and with a magnet for operating the same, conductors or contacts extending longitudinally upon the car, a movable strip extending longitudinally upon the car in proximity to said contacts, whereby said contacts are connected, and a spring for returning said strip and disconnecting said contacts.

12. A controller for a fare-register comprising a movable strip extending longitudinally upon a car and carrying a contact, in combination with a fixed contact or conductor located in proximity, an electrical circuit including both contacts, and an electromagnet in said circuit for operating the register mechanism.

13. In combination with the car structure, a longitudinal recess containing a fixed conductor or contact, in combination with a yielding strip carrying a second conductor or contact, whereby said contacts can be closed by pressure at any point in the length of said strip.

14. In combination with the car structure having a longitudinal groove, a hinged strip adapted to yield and enter said groove, contacts carried in said groove, and upon said strip, and a spring for returning said strip to normal position.

15. In a fare-register and in combination, a units-dial and a tens-dial, disks on the arbors of said dials co-operating to effect the periodical motion of the tens-dial, means for moving one of such disks out of line with the other, cams on the arbors, and resetting devices adapted to act upon said cams and also to operate the means for changing the alinement of the said disks.

16. In a fare-register, a trip-register comprising indicating-dials, an intermittently-movable tooth on the arbor of one dial, a disk on the arbor of the other dial operated periodically by said tooth, means for shifting said disk out of line with said tooth, cams on said arbors and resetting devices adapted to act upon said cams and also to operate the means for changing the alinement of the said disks. 5
17. In a fare-register and in combination a trip-register and a total-register geared together by a clutch, adapted to be disconnected to permit the trip-register to be reset, actuating-disks on the arbors of the trip-register, one of which disks is capable of being shifted on its arbor 8, a sliding pin 41, a slipping device operated by said pin and having arms respectively extending to said arbor 8, and to said clutch, and a resetting-bar having means 15 for operating said pin 41.
18. In a fare-register, a primary operating-lever in combination with alarm mechanism comprising a bell, a striker pivoted to the primary lever, and means for causing the primary lever to apply power first through the long arm of the striker and then through its short arm, substantially as and for the purpose set forth. 25
19. In a fare-register a primary operating-lever, in combination with alarm mechanism comprising a bell and a striker, the striker being pivoted to said lever, means for applying power to the striker first through its long arm and then through its short arm, and a 30 spring connected to its long arm.
20. In an alarm, an operating-lever, in combination with an operated lever forming a bell-striker and having a pivotal connection near its end with the operating-lever, and two variable fulcrums, viz: a fulcrum near the end of its long arm and one near the end of its short arm; whereby power is applied by the operating-lever at the said pivotal point first against the long-arm fulcrum and then against the short-arm fulcrum for the purpose set forth. 45
21. In a fare-register and in combination a magnet and armature, a bell, a bell-striker pivoted near its end upon the armature, and temporary fulcrums for the striker located respectively adjacent to its long and to its short arms; whereby the armature will first apply power to the striker through the favorable leverage of its long arm, and subsequently through the relatively less favorable leverage of its short arm, for the purpose described. 50
22. In combination with an alarm, a magnet, its armature and electrical connections, a striker pivoted to the armature, a yielding buffer situated between the striker and the alarm, a stop situated on the opposite side of the striker and near and beyond its pivotal point, and a spring connected to the striker in opposition to the armature, all arranged to 55 produce the following sequence of operation: the energizing of the magnet, the movement of the striker as a lever whose fulcrum is the
- 70 said yielding buffer, into contact with said stop; the further movement of the striker as a lever whose fulcrum is the said stop; the deenergizing of the magnet, and the retraction of the striker by the said spring.
23. In combination with an alarm, an operating-lever, a striker pivoted to said lever and adapted to be withdrawn from the alarm 75 by said lever, and two points of resistance against each of which the striker bears in turn, each point being a temporary fulcrum for the moving striker, whereby the leverage is changed during the withdrawal of the 80 striker, for the purpose set forth.
24. In a register and in combination, a shaft carrying a direction-dial; an operating-bar slotted to embrace said shaft and carrying a pawl; a polygonal plate on said shaft having 85 projecting pins to be engaged by said pawl; and angularly-placed lugs on the operating-bar normally bearing on said plate at one of its angles, but released therefrom by the movement of the bar which causes said pawl to 90 turn the plate and dial.
25. In a fare-register, the combination with a sliding bar for resetting the registering-dials, of a locking device for compelling a full stroke of said bar in either direction, comprising 95 a rack on the bar, having a tooth projecting beyond the line of the remaining teeth, a pivoted doubly-toothed dog, and a spring for holding the teeth of said dog in engagement with the rack on the up-and-down strokes respectively of the said bar; whereby the said projecting tooth of the rack disengages a tooth of the dog at the end of each stroke and reengages the other tooth. 100
26. In a fare-register a trip-register, a set 105 of impressing-wheels counting synchronously with said register and forming part of a recording device, gearing for driving said register and counting-wheels, means for disconnecting said driving-gearing, a direction-indicating dial, and a support for a record-blank forming the other part of the recording devices, all in combination with a sliding bar carrying means for accomplishing through suitable connections and at a single stroke, 115 the following results; the impressing of a record upon the record-blank, the adjustment of the direction-dial, the disconnection of the gearing and the resetting of the trip-register and the counting-wheels. 120
27. In a fare-register, two counting-wheels mounted upon a common shaft, a pawl carried by one of said wheels for operating the other periodically, an obstruction in the path of said pawl for causing its periodical engagement with the other wheel, and means for mechanically resetting both wheels; such resetting means having a connection with the said obstruction for removing it from the path of the pawl at the time of resetting. 125
28. In a fare-register a shaft, a units-wheel and a tens-wheel mounted side by side thereon, and each provided with a resetting-cam, a gear detachably connected to the units- 130

wheel, and in train with driving-gearing, means for connecting and disconnecting the units-wheel and tens-wheel periodically, means for detaching said gear from the units-wheel, 5 means acting on said cams for resetting both wheels when freed from the gear and from each other, and means for reconnecting the gear to the units-wheel after the resetting.

29. In a fare-register, units and tens counting wheels, a shaft upon which they are loosely mounted, a pawl on the units-wheel, for operating the tens-wheel periodically, a resetting-cam for each wheel, and a detachable gear in train with driving-gearing, for operating the units-wheel; all in combination with a rocking sleeve having independent projecting arms 89, 79, 92 and 91, and with a slid-

ing bar having a projection 90, all constructed and arranged for accomplishing the following results at a stroke of said sliding bar; 20 the rocking of the sleeve by means of the arm 89; the detaching of the gear by the arm 92; the movement of the arm 79 to render the said pawl inoperative, and the resetting of both wheels by the bearing of the arms 91 25 upon said cams.

In testimony whereof I have affixed my signature, in presence of two witnesses, this 7th day of June, 1898.

STEPHEN C. HOUGHTON.
